J. Chase,

Washing Machine,

Patented June 23, 1834

Fig; 1.

Fig; 2.

Githam Chase of Waterville, Maine
Seller's Patent.

The Schedule is annexed to another Githam Patent and making part of the same containing a description in the words of the said Githam Chase himself of his improvement in the washing machine.

To all to whom these Presents shall come,

Be it known that of Githam Chase of Waterville in the County of York and State of Maine have invented a new and useful improvement in the Washing Machine and that the following is a full and exact description of the construction and operation of the said machine as invented or improved by me, viz. first by taking four pieces of Board one inch thick and forming a square Box three feet long eighteen wide, and fourteen inches deep halved together and well nailed. Said Box to be lined on the inside with fluted board three quarters of an inch thick, on trial at the corners of the box the grain of the wood running crossways with that of the outside. There is then put in two ends, made of one inch board, halved into fit, on the inside of these ends are then placed rails, a cross bar in the following manner, viz. by taking hard wood board long enough to reach across the box and halve into the same. The edges to be rounded off placed one and a half inch apart, at one end horizontally, and at the other end perpendicular, at the same distance from each other.

Two cogwheels are then affixed to the centre of the box, one on each side, on one of which is attached a cog wheel of cast iron about one foot in diameter, another wheel with one half the number of cogs made to match with the former, is secured to the frame by a bolt, a belt and sprocket. An iron crank ten inches long with a wooden handle is attached to the small wheel to put the machine in operation.

A frame is then made by taking two pieces of hard wood, just each four feet long and three inches square, and confining them one to the other at each end nineteen inches apart on the inside each piece ten inches square. The frame is then set on four legs, two inches square and two feet long. The machine is then placed on the centre of the frame & turned by the crank as above described. The clothes to be washed are then put into the machine, with a suitable quantity of soap suds, at a door cut out of the centre of the top of the machine two inches square, halved on the inside & having a handle is then put into the machine being fastened to its place and secured by buttons.

The machine now put in operation by turning the crank will change the clothes from one end of the box to the other by revolution of the crank and the wheels.

one to put together that when the handle of the crank is turned... the operator the
box will be in a perpendicular direction. By this method the clothes are kept warm
being confined from the air, are constantly changed from one end to the other striking
with sufficient force on the flats and rails, or crook bars, to cleanse them thoroughly
in less time and with much less labour, than any other machine that I have exam-
ined - Completely. Quilts or woollen garments with buttons on them may be
washed clean in a few minutes without sustaining any injury, and with equal
facility of those of cotton or linen. I claim as my improvement the general form
and operation of the machine with the rails, or crook bars as above described, and
the particular operation of the crank and cog wheel, will satisfy by actual exper-
iment, that it possesses many advantages over any other machine in operation, and
that its simplicity and cheapness, and power of cleaning will make it a valuable
improvement.
